APPARATUS FOR FORMING CENTRIFUGALLY CAST LININGS

Walter Brown, Toledo, Ohio

Application September 22, 1939, Serial No. 296,156

6 Claims. (Cl. 22—203)

The invention relates to the manufacture of composite metal articles composed of two different metals or alloys integrally and continuously bonded together. More particularly, the invention relates to the lining of a preformed metal article either on the inner or the outer surfaces thereof, or on both inner and outer surfaces.

The invention is an improvement on the invention described and claimed in my Patent No. 1,923,075, issued August 22, 1933, and on my co-pending application, Serial No. 56,045, filed December 24, 1935.

In the present state of the art, as shown by my prior patent and pending application above referred to, it is possible to form an integral and continuous bond between metals and alloys of relatively high melting point and preformed metal articles such as shafts and tubes. Essentially the process consists of forming a tubular shell which is hermetically sealed except for a relatively small vent, and placing within this shell prior to sealing the same the desired quantity of metal or alloy which is to be used for the lining. The sealed assembly is then placed in a heating furnace and brought to a temperature which will cause the lining metal to become molten and then the heated assembly is placed in a spinning machine which centrifugally distributes the molten metal until it solidifies and forms the composite article. In the prior methods it has been found that the molten lining metal while within the assembly becomes contaminated with a certain amount of impurity by reason of the molten metal contacting the metal walls of the assembly. Thus where the outer shell is of steel, the lining metal becomes alloyed with a certain amount of iron which in some cases is detrimental to the quality of the lining metal in the finished article.

The principal object of this invention is to prevent any substantial contamination of the molten lining metal during the process. To this end I have devised a process whereby the lining metal is retained within a container during the heating stage of the process and is not allowed to come in contact with the article to which it is to be bonded until the assembly is in condition for the final spinning operation. The container for the molten metal is formed of a material which will not contaminate the lining metal when the latter is in a molten condition, and thus the molten lining metal is maintained free of any undesirable impurities until the moment when the centrifugal casting operation takes place. Since this latter operation requires a relatively short

period of time, very little contaminating material can be picked up by the molten metal.

My invention may be carried out in various different ways which are hereinafter more fully described and illustrated in the accompanying drawing, wherein—

Figure 1 is a longitudinal section through a tube in which a lining is to be formed showing the method of inserting the lining material and preparing the tube for the lining process;

Figure 2 is a diagrammatic view showing the method of spinning the tube of Figure 1;

Figure 3 is a cross section through the tube of Figure 1 after spinning;

Figure 4 is a longitudinal section through an assembly for lining the outer surface of a tubular article;

Figure 5 is a longitudinal section through an assembly for lining both the outer and inner surfaces of bearing shells to form bearings for internal combustion engines;

Figure 6 is a cross section on the line 6—6 of Figure 5;

Figure 7 is a cross section of the finished bearing made with the assembly of Figure 5;

Figure 8 is a longitudinal section through a modified arrangement for lining the outer surface of a solid shaft.

In Figure 1 I have shown an assembly for the lining of hollow tubes on the inside surface only. 10 represents the tube to be lined and 11 and 12 are end plates secured to the tube, preferably by welding as indicated at 13. One of the end plates has a small vent hole 14 which permits the escape of the oxidizing gases during the heating operation and also permits of the introduction of materials which will aid in producing non-oxidizing conditions within the assembly.

The other end plate 11 has welded thereto a short piece of tubing 15 which forms a retainer for the container 16 which is concentric with the outer tube 10. The container 16 is of a size to hold sufficient lining metal to provide for a lining of the desired thickness and, as shown, it extends lengthwise within the outer tube for a substantial proportion of the total length of the outer tube. The container 16 is formed of a material which is inert to the action of the molten lining metal, or at least does not introduce constituents into the molten lining metal which are detrimental to the properties desired. The container may be made, for example, of graphite or porcelain, or any other ceramic material which will remain solid at the temperatures used during the process and at the same time will not re-

act with the molten metal to form undesirable impurities therein.

The lining metal is introduced into the container 16 in the solid state in any desired form which is convenient for loading within the container. It is represented by the numeral 17. After introducing the solid metal, the end plate 12 is secured in position and the assembly is placed in a heating furnace in such a position that the molten lining metal will be retained within the container 16 and will not come into contact with the other parts of the assembly. Thus the assembly should be heated while in a vertical position or at a sufficient incline to prevent gravity flow out of the container. After 15 the assembly has been heated to the desired temperature, it is withdrawn from the furnace and placed in a spinning machine as diagrammatically illustrated in Figure 2. The molten metal then flows by gravity into the bottom of the tube 10, but the machine is immediately set in operation to centrifugally distribute the molten metal so that it uniformly lines the walls of the tube. The spinning is continued until the metal solidifies and it is usual to hasten the solidification by 20 external cooling as by projecting a series of streams of water onto the spinning tube. When the spinning is complete, the tube is removed from the machine, the end plates and the container 16 are severed from the tube, thus leaving the composite metal tubing as illustrated in Figure 3 where 18 represents the inner lining bonded to the outer tube 10.

With the arrangement as described, it will be apparent that the molten lining material is in contact with the walls of the tube 10 for a very short period of time and this prevents any substantial amount of impurities being picked up from the walls of the tube.

Where it is desired to line the outer surface of a tubular article, an assembly as shown in Figure 4 is provided. 19 is the tubular article to be lined and 20 is a relatively thin outer shell. In order to keep the tube and shell concentric, the end plates 21 are provided with cylindrical portions 22 which engage the inner surface of the tube 19. The tube to be lined is provided with perforations 23 to permit the molten metal to be centrifugally distributed into the annular space 24 between the tube and the outer shell. One of the end plates 21 is provided with a cylindrical retainer 15 for receiving a container 16 in the same manner as previously described. Thus by heating the assembly while in a vertical position, the lining metal is retained within the container and the assembly is not placed in a horizontal position until it is entirely ready for spinning so that the molten material has only a momentary contact with the tube and the shell prior to the completion of the casting operation.

My improved process may also be used for lining both the inner and outer surfaces of tubular shells as shown in Figure 5. In this modification, one of the end plates 29 is provided with a retainer 15 for the container 16. The outer shell 27 receives alternate annular steel inserts 26 and spacer rings 28. Slots 30 in the steel inserts permit the molten metal to be distributed to the outer surfaces of the inserts. Sufficient lining metal is introduced within the container 16 to form the desired thickness of lining metal on both the outer and inner surfaces.

Figure 8 shows a modified form of assembly for centrifugally coating a lining metal on the outer surface of a solid shaft. As shown, the shaft 31

is inserted within an outer shell 32 and welded thereto by means of the spacer ring 33. The free end of the shaft 31 is held concentric within the shell by a perforated spacer 34 which engages the outer surface of the shaft 31, leaving the same free for expansion in a longitudinal direction. The shell 32 extends beyond the end of the shaft and has formed within the same a container 35 of sufficient size to hold the required amount of lining metal. This container is formed of an inert material as previously described. To provide a vent for the escape of gases within the shell, the shaft may be drilled as indicated at 36 and 37.

With this modification, the assembly must be heated in a vertical position and retained in this position until the assembly is ready for spinning, thus preventing the molten metal from contamination prior to the spinning operation.

What I claim as my invention is:

1. An assembly for lining articles which comprises an outer shell, a container concentrically arranged within said shell for receiving solid lining material, said container being composed of a material which will not contaminate the lining material when the latter is in molten condition, and means for substantially sealing said shell.

2. An assembly for lining articles which comprises an outer cylindrical tube, end plates secured to said tube, means for venting said tube, a cylindrical retaining tube within said outer tube and secured to one of said end plates, and a container for the lining material supported within said retainer and extending concentrically with said outer tube, said container being composed of a material which will not contaminate the lining metal when the latter is in the molten condition.

3. An assembly for the centrifugal casting of a lining metal on the surface of an article to be lined comprising an outer shell, end plates for said outer shell, and a container for the lining material also within said outer shell, said container being composed of a material which will not contaminate the lining metal when the latter is in the molten state.

4. An assembly for lining articles comprising an outer shell adapted to receive a tubular article concentrically arranged within the same, a tubular container within said tubular article, said container being composed of a material which will not contaminate the lining metal when the latter is in the molten state, and means for substantially sealing the ends of said shell.

5. An assembly for lining articles which comprises an outer shell, means for substantially sealing said shell, a container for receiving solid lining material in communication with said sealed outer shell and concentric therewith, said container being composed of a material which will not contaminate the lining material when the latter is in the molten condition.

6. An assembly for casting a molten metal onto a solid metal article comprising an outer cylindrical metallic shell adapted to receive a solid metal article, a ceramic container within said shell adapted to hold the molten metal to be cast out of contact with said article until the assembly is at the proper temperature for casting, and means for substantially sealing said outer shell to exclude the outside atmosphere during heating and casting.

WALTER BROWN.
